REFRIGERATING APPARATUS

Lawrence A. Philipp, Detroit, Mich., assignor to
 Nash-Kelvinator Corporation, Detroit, Mich., a
 corporation of Maryland

Application October 21, 1938, Serial No. 236,155

4 Claims. (Cl. 62—116)

This invention relates to an improvement in refrigerators, and more particularly to the mounting of the motor compressor unit and condenser in the machine compartment of a refrigerator.

The invention consists of a refrigerator comprising a food storage compartment and a machine compartment preferably located therebeneath. Mounted within the machine compartment is a sealed motor-compressor unit enclosed within a sound absorbing housing for eliminating sound and noise created in the operation of the unit. Associated with the housing is a condenser which is connected with the unit. A power driven fan is mounted within the housing for drawing air into the machine compartment through suitable openings or louvers formed in the door thereof, and which air is drawn first through the condenser and then into the housing for extracting 20 the heat from the condenser and compressor unit and then conducting the air from the housing and delivering it at the front of the refrigerator.

The invention consists of certain novel features 25 of construction and combinations of parts which will be hereinafter described and pointed out in the claims.

In the accompanying drawing:

Fig. 1 is a vertical sectional view of a portion 30 of a refrigerator showing the food and machine compartments with the motor-compressor unit mounted in the machine compartment;

Fig. 2 is a horizontal sectional view on line 2—2 of Fig. 1;

Fig. 3 is a detail view in elevation showing the 35 mounting of the condenser;

Fig. 4 is a detail sectional view illustrating the coupling between the drive shaft for the motor-compressor unit and fan shaft.

The present invention comprises a refrigerator 40 intended primarily for domestic purpose, and consists of a food compartment 11 and a machine compartment 12. The body 10 of the refrigerator is preferably constructed of metal with the wall 45 suitably insulated at 13 for the food compartment.

Mounted within the machine compartment 12 and supported from the bottom 14 of the food compartment is a sealed motor-compressor unit 15, consisting in general of stator windings 16 and a rotor 17 mounted on a drive shaft 18 journaled in a bearing 19 in an end of the unit casting. An eccentric 18 is provided on shaft 18 for operating a piston 20 in the cylinder 21 by means 55 of a connecting rod 22. As this unit is set forth

primarily for illustration, further detailed description is considered unnecessary. The motor-compressor unit 15 is supported vertically in the machine compartment 12 from a bracket 23 secured to the bottom 14 by means of screw-bolts 5 24. Interposed between the ends of the bracket 23 and the bottom 14 is a suitable packing or cushion of rubber 25. Screw bolts 26 pass through the bracket 23 and engage an end of the unit 15 for supporting the unit. Coiled springs 27 are 10 interposed between the bracket 23 and the heads of bolts 26 for resiliently supporting the unit.

A housing 28 is provided for the motor-compressor unit, and is preferably formed of metal lined with acoustic sound absorbing material 29 15 for taking up and absorbing any sounds or noises emanating during the operation of the unit. This housing encloses three sides, top and bottom of the unit, while the front side is open to receive 20 a suitable condenser 30. The condenser is bounded on all sides by the sound absorbing material.

The bottom 31 of the machine compartment 12 is provided with an opening 32 through which 25 the housing 28 extends, and disposed beneath the bottom 31 and extending transversely of the housing 28 is a sound insulated partition 33 which is provided with an air outlet opening 34. The partition 33 is disposed above the bottom 35 of the housing 28 for forming a fan chamber 36 30 therebetween. The fan chamber is provided with a discharge opening 37 at the front of the housing for directing the exhausted air toward the front of the refrigerator.

Mounted within the fan chamber is a centrifugal fan 38 of any approved construction having a fan shaft 39 which projects upwardly through the opening 34 in the partition 33. The shaft 39 is secured to shaft 18 by being screw threaded 40 into shaft 18 as at 41. An end plate 43 is attached to the end of the unit 15 by means of bolts 44 forming a support for shaft 39 which extends therethrough. An oil chamber 45 is formed between the end of the unit and the 45 plate 43, which has communication with the oil groove 46 around the shaft bearing 15' and with the lubricant chamber 47 of the unit by the passage 48. The shaft 39 is sealed against leakage of oil by a seal ring 49 which engages an end 50 of shaft 18. The ring 49 is mounted upon diaphragm 50 immediately above a rubber ring 51 which permits a slight end movement of shaft 18 and continuously tends to urge ring 49 toward the end of shaft 18. By this arrangement any 55

leakage between shaft 18 and ring 49 would be oil leakage only.

The front of the machine compartment is provided with a door 52 having louvers or slots 53 for the admission of air to the compartment. When the motor-compressor unit is in operation the fan 38 will be rotated causing air to be drawn into the compartment 12 and through the condenser 30 for extracting the heat therefrom. This 10 air is drawn into the housing 28 and over the unit for cooling the motor and compressor. The heated air is then drawn through the opening 34 of the partition 33 into the fan chamber 36 where it is discharged into the room at the front 15 of the refrigerator thereby permitting the refrigerator to be placed tightly against the wall of a room.

The insulation of the housing 28 will dampen and absorb all sounds and noises created by the 20 motor unit and fan and thereby eliminate all objectionable sounds generally emanating from a machine of this character.

The food compartment 11 is provided with any suitable evaporator 55, which receives refrigerant 25 from the motor-compressor unit 15, by conduit 56 leading from a high side float receiver 57, and which is connected to the condenser 30 by a conduit 58. The refrigerant is delivered to the condenser from the unit 15 by a conduit 59. A 30 conduit 60 conducts the vaporized refrigerant from the evaporator to the unit 15. The conduits 56 and 60 extend through a passage 61 in a post of the cabinet in conducting the refrigerant from and to the evaporator in the food compartment and from and to the compressor in the machine compartment.

From the foregoing it will be apparent that the motor-compressor unit and condenser can be mounted within the machine compartment 12 as 40 a unit, and in providing a sound insulating housing for these elements a much quieter refrigerator is provided as all sounds emanating from the operation of the parts will be readily absorbed by the insulation. Furthermore, the condenser 45 will be cooled by air drawn into the compartment 12 by a fan located within the base of the insulated housing 28, so that the air will first be drawn through the condenser and then over the motor-compressor unit and extracting 50 the heat therefrom, whereupon the air is discharged from the housing 28 toward the front of the refrigerator cabinet.

What I claim is:

1. A refrigerator comprising a sound insulated 55 housing having an opening in a wall thereof, a condenser mounted in said opening, a motor-compressor unit received in said housing, a fan in said housing and having driving connection with said unit, and a partition in said housing 60 for forming a fan chamber and an outlet flue

for the heated air, said partition being provided with an opening for establishing communication between the housing containing the unit and the fan chamber so that air may be drawn by the fan through the condenser and into the housing 5 and exhausted through the fan chamber to the atmosphere in cooling the parts.

2. In a refrigerator, the combination of a food compartment and a machine compartment, said machine compartment having the bottom there- 10 of provided with an opening, a motor-compressor unit resiliently supported within said machine compartment, an insulated sound absorbing housing enclosing said motor-compressor unit for absorbing sounds emanating therefrom dur- 15 ing operation and extending through the opening in the bottom of said machine compartment, said housing being provided with an opening in the wall thereof for the reception of a condenser, a sound insulated partition in said housing ar- 20 ranged in a plane parallel to the bottom of said machine compartment and the bottom of the housing for forming a fan chamber, said partition having an opening therein for forming com- 25 munication between the housing and the fan chamber, and a fan in said fan chamber having driving connection with said unit for drawing air through the condenser and into the housing for cooling the condenser and unit and thence into the fan chamber and exhausting the air 30 from the fan chamber beneath the machine compartment.

3. In a refrigerator, the combination with a cabinet having a food and a machine compartment, of a sound absorbing housing of consider- 35 ably smaller size than said machine compartment and being removably mounted therein and having an opening in its front wall and an opening in a bottom wall, a condenser mounted in the opening in said front wall, a compressor mounted 40 in said housing and a flue positioned adjacent said bottom wall and leading toward one wall of said refrigerator.

4. In a refrigerator, a sound insulated housing comprising a pair of chambers having a dividing 45 wall therebetween, said dividing wall having an opening therein to provide a passageway between said chambers, one of said chambers forming a compressor chamber and having an air inlet opening in a wall thereof, a condenser adjacent 50 said inlet opening, a compressor mounted in said compressor chamber, the other of said chambers forming a fan chamber and having an air outlet opening through a wall thereof, and a fan in said fan chamber for first drawing air 55 through said air inlet opening about said condenser, then through said compressor chamber about said compressor and into said fan chamber for discharge through said outlet opening.
